CLAIM

The ornamental design for a wire egg separator, as shown and described.

DESCRIPTION

FIG. 1 is a perspective view of the inventive design for a wire egg separator;

FIG. 2 is a top plan view of the FIG. 1 design;

FIG. 3 is a side elevational view of the FIG. 1 design;

FIG. 4 is a bottom plan view of the FIG. 1 design;

FIG. 5 is an opposite side elevational view of the FIG. 1 design;

FIG. 6 is a rear end view of the FIG. 1 design; and,

FIG. 7 is a front end view of the FIG. 1 design.

1 Claim, 2 Drawing Sheets

FIG. 3

FIG. 4

FIG. 5
